B. C. Painter,
By act of 13th Congress.

United States Patent Office.

BENEVILLE C. PAINTER, OF MECHANICSBURG, PENNSYLVANIA.

Letters Patent No. 70,740, dated November 12, 1867.

IMPROVEMENT IN FLASKS FOR CASTING TUYERES.

The Schedule referred to in these Letters Patent and making part of the same.

TO ALL WHOM IT MAY CONCERN:

Be it known that I, BENEVILLE C. PAINTER, of Mechanicsburg, in the county of Cumberland, and State of Pennsylvania, have invented certain new and useful Improvements in Flasks or Moulds for Casting Tuyeres; and I do hereby declare the following to be a full, clear, and exact description of the same, reference being had to the accompanying drawings, making a part of this specification, in which—

Figure 1 represents an elevation of one of the sides of the mould or flask.

Figure 2 represents a longitudinal vertical section through the same.

Figure 3 represents a top plan of the mould or flask with the pattern in place, and as it appears when the upper section is removed; and

Figure 4 represents a vertical transverse section through the mould.

Similar letters of reference, where they occur in the separate figures, denote like parts in all of the drawings.

From the irregular form and shape of a blacksmith's tuyere it is extremely difficult to mould and cast it in one piece, requiring great care, very large flasks, and an unusual amount of ramming of sand around the pattern and in the mould or flask, so much so as to make these tuyeres very expensive. The object and purpose of my invention is to expedite and cheapen the expense of moulding tuyeres; and to this end I have invented a mould or flask, which I will explain, by which I reduce the cost of moulding and casting to one-half of the cost as heretofore practised; and my invention relates to this mould or flask, which I shall now describe.

The mould or flask is composed of three sections, A B C, one overlying the other, as shown in the drawings. In addition to these three sections there is a false bottom, D, in the middle section, which is quite material, and a cover, E, which is not so material to the result. There is also at one side and end of the middle section B a slide, F, which closes an opening through which the pipe G is moulded into the flask and united to the body of the tuyere by the molten metal flowing around it, and H is a support for holding this pipe G, which is previously cast, and which in the finished tuyere becomes the channel for the introduction of the blast into and through the tuyere.

To mould the tuyere in this flask I proceed as follows: The sections are separated, and the pattern J and L being placed on a follow-board, the central section B is now placed over the pattern J and L, and this central section has a partition, K, across it and dead space outside of it. When this central section is rammed up over the pattern L with moulding-sand to the height of the partition K, the false bottom D is inserted through the openings in the sides of the middle section, which bottom is held and firmly supported by cross-pieces b b. The false bottom being thus in place, the ramming proceeds around the pattern J, and at the proper height thereon, where the tube G is to be united to the body of the tuyere, a conical ferrule, c, is introduced, by means of which the molten metal is allowed to flow around the end of the tube and thus fasten it to the body of the tuyere, as follows: The ferrule c is put on the tapered end of the tube G, as shown in fig. 4, and adjusted to the pattern J, through a hole in section B at the end of the slide F, and it is then rammed into the top of the pattern J. The lower section A, which has a partition, I, across it, and dead space outside of that partition, is now placed on the central section and rammed around and over the bottom and end of pattern J, as seen at a a, figs. 2 and 4, and which, when cast, becomes the body of the tuyere. The two sections now rammed up are inverted, and section A becoming the lower one, and section B on top of it. The section C is then placed on section B, and rammed up, with suitable channels in it to receive the fluid metal. Section C is then lifted off from section B, and the pattern L (forming what in the finished tuyere may be termed the valve-trunk or air-trunk for supplying draught to the fire, enough to keep it alive when the blast is off) is then taken out. Section B is then lifted off from the lower section A, leaving the pattern J on the lower section. The ferrule c is then taken out by pushing the tube G, resting on its support H, inward a distance equal to the thickness of the metal when cast. The ferrule c is then drawn off from the end of the tube from the inside. The sections now may be put together and properly united by hooks, clamps, or otherwise, and the molten metal can be poured into the mould. The metal flowing around unites the tube to the body of the tuyere. When the finished casting is to be removed, the slide F must be removed from its section to allow the tube which projects from the flask to pass out. It is, of course, understood that suitable cores are used to cast the tuyere hollow for the admission of air through it,

and with an opening below through which it may be cleaned out, and that the sections are furnished with suitable guides, by which they are matched or put together.

Having thus fully described my invention, what I claim therein as new, and desire to secure by Letters Patent, is—

1. In combination with the sections A B of the flask, the partitions I K and false or removable bottom D, arranged as and for the purpose described.

2. I also claim, in combination with the previously-made tube G, the ferrule *a* and slide F in the section B, for the purpose of moulding in the tube and removing the finished casting from the flask, substantially as described.

B. C. PAINTER.
